UNITED STATES PATENT OFFICE.

HENRY E. SHAFFER, OF ROCHESTER, NEW YORK.

BURNER FOR ACETYLENE GAS.

No. 866,163.

Specification of Letters Patent.

Patented Sept. 17, 1907.

Application filed October 15, 1906. Serial No. 339,113.

To all whom it may concern:

Be it known that I, HENRY E. SHAFFER, a citizen of the United States, and a resident of Rochester, in the county of Monroe and State of New York, have invented 5 certain new and useful Improvements in Burners for Acetylene Gas, of which the following is a specification.

This invention relates to burners for acetylene gas, and consists in the apparatus hereinafter described and claimed.

10 The object of the invention is an improved burner in which a larger amount of air is led to the gas jet and is better mixed with the issuing gas than in burners heretofore constructed.

In the drawings:—Figure 1 is a top plan view of a 15 burner embodying this invention; Fig. 2 is a vertical section on the line 2—2 of Fig. 1; Fig. 3 is a like vertical section through a burner of slightly modified form; Fig. 4 is a top plan view of one of the arms of the burner of Fig. 3.

20 All of the devices herein shown are of the twin-burner variety, in which two jets of mixed acetylene gas and air impinge to form a flat flame. In the manufacture of these burners, a brass tube 1, Fig. 3, is employed, in which a two branch tip is set, each branch adapted to 25 produce a jet such as above mentioned. In Figs. 1 and 2 is shown a tip or burner body in which two branches or arms 2 and 3 are set at a suitable angle to each other, such as a right angle. In the upper surface of each branch a channel or slot (4 or 5) is cut transversely, so 30 that the planes of the two channels intersect, and the channel is open at its ends for free induction of air to the point in the channel where the gas jet passes through it. The bottom of these channels has an enlargement hereinafter described constituting an air channel.

35 The upper edges of the channel overhang the said enlargement thereof. At the middle of the bottom of each slot, and in a plane parallel to the sides thereof, is bored the small gas duct (6 or 7) which communicates with the other gas duct (8 or 9) extending up the branch 40 (2 or 3,) from the chamber 10 in the base of the tip. The base 11 is adapted to fit in the tube 1 above mentioned. The ducts 6 and 7 are bored so that their axes intersect.

As the acetylene gas passes from the chamber 10, 45 and through the ducts 8 and 6, or 9 and 7, it issues into the bottom of the slot or air channel 4 or 5, and, by the force of its ejection, draws in air through the ends of the channel 4 or 5, so that said air comes from two directions to meet the jet of acetylene at the point of its issuance; and on account of the large cross section of the channel 4 or 5, with reference to the area of the duct 6 or 7, an ample quantity of air for the complete combustion of the acetylene will be mixed with the acetylene, and this mixing will begin at the point of issuance 50 of the acetylene jet, and will continue to mix with said jet and throughout the flame which commences at the

point where the two jets meet. The air has free access laterally to the jet from its emergence from the duct 6, 7, to the emergence of the mixed air and gas from the burner. It will be noted that the acetylene duct 6 or 7, or 16, in Figs. 2 and 3, is of small diameter relatively to the width of the channel through which it emerges, and that said duct enters the open channel above it at the middle point of the bottom of said channel, and discharges a jet of gas directly toward a point in the open 65 top of the channel and in a line midway between said opposite sides. In other words, the jet issuing from the acetylene duct is not directed towards either side of the channel, but issues freely from the open top of the channel. It is found that this large supply of air directed to the jet at the point of issuance and throughout the path of the jet, and through a slot of such size that the jet does not light back to the mouth of the duct 6 or 7, produces an efficient flame of high intensity and without the deposit of carbon upon the burner around 70 the orifice from which the jet of mixed air and gas issues or at the discharge point of the small gas duct. 75

In Fig. 2 is shown an enlargement of the bottom of the channel by cutting a transverse slot 12 or 13, thereby producing an inverted T-shaped slot. This constitutes an enlargement of the bottom of the transverse air slot, so as to increase the amount of air which is led to the acetylene jet at or near its point of issuance from the duct 6 or 7. This form gives even a greater supply 80 of air for the combustion of the acetylene, and by reason of the slight constriction in the outer portion of the slot, there is a greater mixture of the acetylene and air before it emerges from the burner. The orifice where the air and acetylene issue from the burner must, as above stated, be of such size as to prevent a 85 lighting back. 90

In Figs. 3 and 4 is shown another form of burner embodying the same invention, in which the air chamber has an enlargement at the bottom and the enlargement has sides converging to the position of the gas jet in circular curves. In this case there is a transverse slot 14 or 15 in the burner, and beneath it from each side of the burner arm is a circular slot shown by the dotted lines in Fig. 4. The two circular slots intersect in a plane which passes through the acetylene duct 16, as shown 95 in Fig. 4, and in the form shown the slots or enlargements of the channel have parallel top and bottom surfaces. This produces a great efficiency, but the exact accuracy of construction just described is not absolutely essential. In this form of burner, the outer end of the lower portion of the air channel is larger than the inner end thereof, so that the air that is drawn in by the jet of acetylene gas enters more freely and is condensed and concentrated on said jet, and thus there is caused a more forcible and more thorough mixing of 100 the acetylene and air close to the point of issuance of the acetylene, and as the jet passes out through the 105 110

more constricted portion of the channel 14 or 15. By the circular converging sides the air is directed laterally against all parts of the surface of the issuing jet of acetylene.

5 The enlargement constituting the bottom of the channel, as shown in Figs. 2 and 4, causes an overhanging of the edges of the channel over the enlargement. The said enlargement constitutes an air conduit for leading air to the jet of acetylene gas and also under and along 10 the said overhanging edges for keeping the latter cool. The said overhanging edges are thin, and fresh air is constantly moving to all parts of such edges by reason of the suction produced by the acetylene jet, and these overhanging edges are kept cool by the air above, underneath and on the opposite faces of each, in a manner that is impossible without such overhanging construction. It is well known among those versed in this art that unless the burner is kept cool at the point where the acetylene jet emerges from it, there will be 15 an accumulation of a wax-like black material that will finally clog the orifice and interfere with the production of the flame; but if the edges of the orifice are kept properly cool, this accumulation will not take place. This invention is particularly adapted to accomplish 20 this result, and the form of device shown in Figs. 3 and 25 4, in which the sides of the enlargement underneath the said overhanging edges is such as to induce the maximum induction of cool air to each point of the slot or channel through which the jet issues; and in this 30 form of the invention, fresh air can pass directly to the central portions of the channel without being first heated by contact with outer portions of the same channel, because the sides of the channel converge, and air entering on these converging lines can pass directly 35 to different portions of the channel; and at the same time the fragile overhanging portions of the slot are supported at their centers by the intersecting sides of the enlargement as shown by the dotted lines in Fig. 4.

In the forms of the burner shown no drilling is necessary except for the acetylene ducts. The air passages and the passages where the mixed air and gas emerges, need not be drilled. In each of these burners the air inlet channel has portions extending laterally from the portion of the gas jet and in all the forms 45 the outer ends of the said portions are at least as large at the open ends as at the acetylene jet. In one of the forms the outer ends of the channel are larger than at the jet.

The ample air supply to the gas jet and the large 50 space within which the air mixes with the gas, and the fact that the jet is not choked or restricted in its path, cause a very complete combustion of the gas. The large air supply and the mode of bringing the air to the gas keeps this burner cooler than others.

55 What I claim is:—

1. In an acetylene burner, a burner body having two arms for causing a jet issuing from one arm to impinge upon a jet issuing from the other arm; a channel in the upper face of each arm having an enlargement constituting the bottom thereof, whereby the upper edges of the channel overhang the said enlargement, the said channel and enlargement having a bottom and opposite sides and being open at the top and at the ends; and an acetylene duct, of a diameter less than the width of the channel, entering 60 the said bottom midway between the sides and discharging a jet of gas directly toward a point in the top of the

channel and in a line midway between said opposite sides.

2. In an acetylene burner, a burner body having two arms for causing a jet issuing from one arm to impinge upon a jet issuing from the other arm; a transverse channel in the upper face of each arm and entirely across the same, and having an enlargement constituting the bottom thereof, whereby the upper edges of the channel overhang the said enlargement, the said channel and enlargement having a bottom and opposite sides and being open at the top and also at the ends in opposite sides of the arm; and an acetylene duct, of a diameter less than the width of the channel, entering the said bottom midway between the sides and discharging a jet of gas directly toward a point in the top of the channel and in a line midway between said opposite sides. 70

3. In an acetylene burner, a burner body having two arms for causing a jet issuing from one arm to impinge upon a jet issuing from the other arm; a channel in the upper face of each arm having an enlargement constituting the bottom thereof open at the ends and having sides converging inwardly to the position of the acetylene jet, whereby the upper edges of the channel overhang the said enlargement, the said channel and enlargement having a bottom and opposite sides and being open at the top and 80 at the ends; and an acetylene duct, of a diameter less than the width of the channel, entering the said bottom midway between, and at the intersection of, the sides and discharging a jet of gas directly toward a point in the top of the channel and in a line midway between said opposite sides. 85

4. In an acetylene burner, a burner body having two arms for causing a jet issuing from one arm to impinge upon a jet issuing from the other arm; a channel in the upper face of each arm having an enlargement constituting the bottom thereof open at the ends and having sides converging inwardly to the position of the acetylene jet, whereby the upper edges of the channel overhang the said enlargement, the said channel and enlargement having a bottom and opposite sides 90 and being open at the top and at the ends; and an acetylene duct, of a diameter less than the width of the channel, entering the said bottom midway between, and at the intersection of, the sides and discharging a jet of gas directly toward a point in the top of the channel and in a line midway between said opposite sides. 95

5. In an acetylene burner, a burner body having two arms for causing a jet issuing from one arm to impinge upon a jet issuing from the other arm; a channel in each 100 arm having an enlargement connected with the bottom of said channel and being open at its ends in opposite sides of the arm and having sides converging inwardly to the position of the acetylene jet; and an acetylene duct, of a diameter less than the width of the channel, entering the said bottom and discharging a jet of gas in a line extending directly from the duct to a point in the top of the channel and in a 110 line midway between said opposite sides.

6. In an acetylene burner, a burner body having two arms for causing a jet issuing from one arm to impinge upon a jet issuing from the other arm; a channel in each arm having an enlargement connected with the bottom of said channel and being open at its ends in opposite sides of the arm and having sides converging inwardly in intersecting circular curves to the position of the acetylene jet; and an acetylene duct, of a diameter less than the width of the channel, entering the 115 said bottom and discharging a jet of gas in a line extending directly from the duct to a point in the top of the channel. 120

7. In an acetylene burner, a burner body having two arms for causing a jet issuing from one arm to impinge upon a jet issuing from the other arm; a channel in the upper face of each arm having an enlargement constituting the bottom thereof and having parallel bottom and top surfaces and being open at the outer ends at the sides of each arm and having sides converging inwardly to the 125 position of the acetylene jet; and an acetylene duct, of a diameter less than the width of the channel, entering the said bottom at the point of intersection of the converging sides and midway between the sides and discharging a jet of gas in a line extending directly from the duct to a 130 point in the top of the channel.

8. In an acetylene burner, a burner body having two arms for causing a jet issuing from one arm to impinge upon a jet issuing from the other arm; a channel in the upper face of each arm having an enlargement constituting the bottom thereof and having parallel bottom and top surfaces and being open at the outer ends at the sides of each arm and having sides converging inwardly to the 135 position of the acetylene jet; and an acetylene duct, of a diameter less than the width of the channel, entering the said bottom at the point of intersection of the converging sides and midway between the sides and discharging a jet of gas in a line extending directly from the duct to a 140 point in the top of the channel. 145

8. In an acetylene burner, a burner body having two arms for causing a jet issuing from one arm to impinge upon a jet issuing from the other arm; a channel in the upper face of each arm having an enlargement constituting the bottom thereof and having parallel bottom and top surfaces and being open at the outer ends at the sides of each arm and having sides converging inwardly in intersecting circular curves to the position of the acetylene jet; and an acetylene duct, of a diameter less than the width of the channel, entering the said bottom at the point of intersection of the converging sides and midway between the sides and discharging a jet of gas in a line extending directly from the duct to a point in the top of the channel. 10
